MICROSCOPE ILLUMINATOR

Edward N. Esmay and Paul A. Hoogesteger, Brighton, N.Y., assignors to Bausch & Lomb Incorporated, Rochester, N.Y., a corporation of New York

Filed Feb. 23, 1967, Ser. No. 5,912

Term of patent 14 years

(Cl. D57—1)

FIGURE 1 is a front perspective of a microscope illuminator showing our new design; the fragmentary broken lines representing the microscope are shown for illustrative purposes only; and FIGURE 2 is a top plan view thereof.

The dominant features of our design reside in the portion shown in full lines. The side not shown is a mirror image of the side shown.

We claim:

The ornamental design for a microscope illuminator, substantially as shown and described.
